UNITED STATES PATENT OFFICE

153,756

DESIGN FOR AN AUTOMOBILE SERVICING UNIT

Basil A. Beaver, Minneapolis, Minn.

Application February 4, 1948, Serial No. 144,276

Term of patent 14 years

(Cl. D52—2)

To all whom it may concern:

Be it known that I, Basil A. Beaver, a citizen of the United States, residing at Minneapolis, in the county of Hennepin, State of Minnesota, have invented a new, original, and ornamental Design for an Automobile Servicing Unit, of which the following is a specification, reference being had to the accompanying drawings, forming part thereof.

Figure 1 is a perspective view of an automobile servicing unit, embodying my new design.

Figure 2 is a perspective view like that of Figure 1 but showing the side panel removed and the front door opened.

Figure 3 is a fragmentary perspective view, on a somewhat enlarged scale, looking generally from the left of Figure 1 and showing the rear end of unit with the back and top doors open.

Figure 4 is a fragmentary front elevational view showing the upper portion of the reel-housing and the control and meter housing.

The side not shown in the drawings generally resembles the side illustrated in Figure 1, in appearance.

The oil-drums and grease-guns shown in broken lines are for illustrative purposes only.

I claim:

The ornamental design for an automobile servicing unit, as shown, and described.

BASIL A. BEAVER.
